CLAIM

The ornamental design for a radiant heat floor panel, as shown and described.

DESCRIPTION

FIG. 1 is a top plan view of a radiant heat floor panel incorporating our new design.

FIG. 2 is a perspective view.

FIG. 3 is a front elevational view.

FIG. 4 is a right side elevational view.

FIG. 5 is a left side elevational view.

FIG. 6 is a rear elevational view; and,

FIG. 7 is a bottom plan view.
